GLAZING STRIP

Rolf A. Lundberg, 6A Sigyns Vag,
S-14900 Nynashamn, Sweden

Filed July 30, 1973, Ser. No. 383,541

Claims priority, application Sweden Jan. 31, 1973

Term of patent 14 years

Int. Cl. D25—01

U.S. Cl. D13—6

The single figure is a perspective view of a glazing strip, embodying my new design.

I claim:

The ornamental design for a glazing strip, substantially as shown and described.
